UNITED STATES PATENT OFFICE

EMIL BOMMER, OF BROOKLYN, NEW YORK

DOOR CHECK AND CLOSER

Application filed April 17, 1930. Serial No. 444,970.

This invention relates to a door check and closer, more particularly to a double acting hinge and check for use in connection with doors which are intended to be opened in either direction from an initial position; and the invention has for its object and purpose the provision of an improved construction of this character for insertion in a recess or cut in the floor, and one which will embody certain desired features of simplicity, efficiency and convenience.

One object of the invention is the provision of a construction which will eliminate leakage of the checking liquid. To accomplish this object my invention comprehends the provision of an organization of parts so constructed and arranged that the parts may be assembled for operation in a hollow one-piece casting furnished with openings for the introduction, assembly and adjustment of the parts, and with screw plugs for closing and sealing the openings. In carrying out my invention in its preferred form of construction, the parts are so arranged that one of the plugs will carry a screw stem for regulating the liquid compression from the outside of the casting.

Another practical object of the invention is the provision of a construction having a through by-pass for the checking fluid, such by-pass consisting of an intermediate by-pass chamber and two separate channels, one through which the checking liquid must flow in order to reach the by-pass chamber and another through which the checking liquid must flow from the by-pass chamber to the valve means for regulating the discharge of the checking liquid. Each of the channels has a port adapted to communicate with the by-pass chamber, and according to a feature of my invention, the longitudinal dimension of the by-pass chamber is equal or substantially equal to the length of the piston stroke less the diameter of one port. Under this arrangement, a little before the door reaches its initial position, the ports will be covered or approximately covered, so that the complete closing of the door will have to be effected by the natural leakage from around the ports. As a result, the completion of the

closing movement of the door is slowly effected and the door will not be forced over its initial center line.

Other objects and aspects of the invention will appear hereinafter.

The invention resides in the improved door check and closer and in the form, construction and relative arrangement of its several parts, as will be hereinafter more fully described and claimed.

The invention will be best understood by referring to the accompanying drawings, forming a material part of this application, and in which:

Fig. 1 represents a longitudinal sectional view through a door check and closer embodying my invention, this view also showing a fragmentary sectional view of the lower portion of a door;

Fig. 2 is a fragmentary sectional view on a smaller scale, showing the relative positions of the cylinder and by-pass chamber when the door is in open or approximately open position;

Fig. 3 is a cross section taken on the line 3-3 of Fig. 1; and

Fig. 4 represents another cross section taken on the line 4-4 of Fig. 1.

The preferred form of construction, as illustrated in the accompanying drawings, comprises a case in the form of an elongated hollow casting 10 which, in accordance with the usual practice, is placed in a cut or cavity in the floor. The casting is produced with circular openings 11, 12, 13, 14 and 15; it being noted that the openings 11, 12, 13 and 14 are in the top wall 16 of the casting, while the opening 15 is provided in the front end thereof. The walls defining these openings are screw-threaded, and for closing and sealing these openings, I provide the respective screw plugs 11', 12', 13', 14' and 15'. In conjunction with the screw plugs, suitable gaskets may of course be employed in the usual way in order to insure a liquid tight seal.

In the illustrative embodiment, the screw plug 11' constitutes a bearing for the vertical pintle 17 furnished at its lower end with an anti-friction device 18, capable of being

55

100

mounted in a seat 19 produced for the purpose in the bottom wall 20 of the casting. The upper end of the pintle, exteriorly of the bearing 11', is fitted in a bar 21 which is 5 suitably secured to the bottom edge of the door 22.

Within the casting, there is arranged an actuating yoke 23, having spaced arms 23' with longitudinally extending slots 23''. In 10 accordance with the usual practice in check and closer devices of this general character, the pintle 17 is passed through the slots 23'' of the yoke arms 23' and united with the pintle is a cam 24 which works between the 15 yoke arms 23' in a manner to contact with rear rollers 25, of which, in accordance with the usual practice, there are two—a right roller and a left roller. With the right and left rollers 25, mounted between the yoke 20 arms 23', the cam 24 cooperates so as to hold the door open in either direction at the position desired from the initial or closed position. Secured to the cam 24 is a forwardly 25 projecting guide cam 26 which cooperates with a front roller 27 so as to provide for the complete revolution of the pintle. Said front roller 27 is mounted between the yoke arms 23' as shown. Under this arrangement, the device of my invention can be utilized either 30 with a right-hand door or a left-hand door; and the door, whether of the right-hand type or left-hand type, can be moved as far as the door casing will permit.

As clearly illustrated in Figs. 1, 3 and 4, the casting at a suitable point forwardly of the position of the pintle is produced with a vertical wall or partition 28 having a central circular bearing 29 in which a cylinder 30 is fitted for reciprocatory movement. Said 40 cylinder is made with a head portion 31 and rearwardly of said head portion it is secured to the yoke 23 by means of a coupling pin 32. For the application of the coupling pin, the cylinder is provided with an opening 31' in 45 alignment with a seat 31'', while the yoke 23 has a transverse opening 32' therein. These parts are so arranged and proportioned that, during assembly, after the cylinder has been so positioned that its opening 31' and seat 31'' are in alignment with the yoke opening 32', the coupling pin 32 may be introduced through the opening 12 in the top wall 16 of the casting; it being manifest, of course, that in order thus to apply the coupling pin, the pintle must be turned until the yoke is drawn rearwardly sufficiently to bring the opening 32' in alignment with the said opening 12 of the top wall 16, when the cylinder can also be moved rearwardly in its bearing 29 and adjusted therein until its opening 31' and seat 31'' are properly aligned with the opening 32' and opening 12 for the application of the coupling pin.

The cylinder 30 slidably embraces an annular head 33 provided on the rear portion of

a stem-body or plunger 34. At its forward end the cylinder 30 has screw-threaded therewith at 35 a sleeve 36 which slidably embraces the stem-body, as shown. Said stem-body constitutes a stationary element and is secured in place to the screw plug 15' by means of a suitable screw 37 which is threaded transversely through the center of the screw plug 15' and into the forward end of the stem-body 34. With this construction, the rear end 55 of the stem-body in conjunction with its head portion 33, forms an end chamber 38 in conjunction with the cylinder. Also, as shown in Fig. 1, an annular chamber 39 is formed around the stem-body, such annular chamber 50 being defined by the stem-body itself, head portion 33, cylinder 30 and the rear end of the sleeve 36. The cylinder 30 has one or more openings 40 which provide communication between the annular chamber 39 and the main oil or liquid chamber 41. In the head portion 33 of the stem-body, suitable ball check valves as 42 are arranged, which valves open in the usual manner to permit the checking liquid to pass from the annular chamber 39 into the end chamber 38 during the rearward movement of the cylinder 30 as the door is opened in either direction, and which, on the other hand, close under pressure to prevent the liquid from passing reversely, that is to say, from the end chamber 38 into the annular chamber 39 during the forward movement of the cylinder under closing action of the door to initial position.

According to an important feature of my invention, the sleeve 36 is provided adjacent the stem-body with a by-pass chamber 43, and the stem-body is provided with two separate axial by-pass channels 44 and 45. As will be observed in Fig. 1, the by-pass channel 44 leads from the end chamber 38 and has a port 44' adapted to communicate with the by-pass chamber 43, while for the other channel 45 there is a port 45' which is adapted to communicate with the by-pass chamber 43, the last-named channel 45, at a point forwardly of the sleeve 36 having a lateral duct 46 which communicates with the main chamber 41. According to a feature of this arrangement, the by-pass chamber 43, which surrounds the stem-body, has a longitudinal dimension substantially equal to the length of the cylinder stroke less the diameter of one port, that is to say, either of port 44' or of port 45'. Under this arrangement, under the rearward movement of the cylinder, resulting from the opening movement of the door, the two ports 44' and 45' are in communication with the by-pass chamber 43, providing thereby a through by-pass from the end chamber 38 to the main chamber 41, such through by-pass obviously consisting of the channel 44, port 44', by-pass chamber 43, port 45', channel 45 and duct 46. The checking liquid, therefore, is thus permitted to escape by a through by-

pass during the return movement of the cylinder until, just before the termination of the forward cylinder stroke, the by-pass chamber 43, which is equal to the length of the 5 cylinder stroke less the diameter of one port, causes the ledge 36' of the sleeve to cover the ports 44' and 45'. Owing to this arrangement, the slight remaining distance which the cylinder must travel in order to reach the 10 forward terminal of its stroke, in which position the door is on its center line, must be effected by the natural leakage of the checking liquid about the ports 44' and 45' at the points where they come in adjacency to the ledge 36'. 15 Through this arrangement, therefore, provision is made for rapid closing of the door up to a point relatively close to that in which the door occupies its initial position, but after the door has reached this point, its further 20 closing movement is slowly effected, owing to the slow leakage about the ledge 36', with the result that the door will close to its initial position and not pass beyond the center line to the right, or to the left. 25 A compression spring 47 is employed to effect the return movement of the cylinder and hence the closing movement of the door, said spring being mounted around the cylinder 30 and imprisoned between the 30 forward end of the partition 28 and a stop disk 48 which is screw-threaded upon the exterior of the sleeve 36. Manifestly, the tension of the spring 47 may be regulated by adjusting the position of the 35 stop disk 48 upon the sleeve; and in order to provide means whereby readily to effect the adjustment of the stop disk by means of a suitable tool through the opening 13 of the casting top, a series of radial openings 49, 40 each receptive of a manipulating tool, is provided in the periphery of the stop disk 48. The sleeve 36 is adjustable with respect to the cylinder 30 and for this purpose the periphery of the sleeve may be provided with 45 suitable tool receiving openings as 50. Adjustment, therefore, of the sleeve 36 as well as of the stop disk 48, may be effected by a tool manipulated through the opening 13.

According to another important feature of 50 my invention, the stem-body 34 forwardly of the sleeve 36 and where it contains the duct 46 is of a reduced diameter and is surrounded by a ring 51, having a duct 52 adapted to be put into register with the duct 46 as shown in 55 Fig. 3. Now, the ring 51 is provided with a crank in the form of a yoke having spaced arms 53. An adjusting pin 54, which is screw-threaded at 55 in the screw plug 14', has a head 56 which is adapted to turn between the two crank arms 53 as clearly depicted in Fig. 3. By adjusting the pin 54, the ring can be turned upon the stem-body so as to adjust the position of the duct 52 with respect to the duct 46. In this way, provision is 60 made for regulating the discharge of liquid

into the interior of the case; and it will be observed in this connection that the pin 54 can be adjusted from the exterior of the casting.

As illustrated in Figs. 1, 3 and 4, the oil or liquid employed in the casting as the checking medium, can flow from the main chamber 41 into the rear chamber 57 through suitable apertures 58 provided for the purpose in the partition 28.

As best shown in Figs. 3 and 4, the top wall 16 of the casting is preferably formed with laterally projecting flanges 59 adapted to be placed in mortise cuts in the floor and adapted to receive therein securing means as 60 for the purpose of firmly fastening the casting to the floor.

In assembling my improved check and closer, the screw plugs are of course first removed from the casting. The pintle 17 with the yoke 23 attached is inserted through the opening 11, the anti-friction device fastened to the lower end of the pintle being operatively seated in the bearing 19 in the bottom wall 20. The coiled spring may then be inserted through the end opening 15, whereupon the cylinder 30, stem-body 34 and sleeve 36 may all be introduced through the opening 15, the cylinder being directed through the coil of the spring and into position to seat in the bearing 19 for adjustment therein to the position with respect to the yoke that will permit the application of the coupling pin 32. The stop disk 48 may then be applied and the spring properly tensioned. The valve ring 51 and adjusting pin 54 therefor may then be applied and manipulated to effect the desired adjustment between the ducts 52 and 46. When the checking liquid has been introduced and the screw plugs properly applied, there is no leakage of the checking liquid owing to the operation of the working parts. As hereinbefore intimated, both the sleeve 36 and the stop disk 48 may be adjusted at any time upon removing the screw plug 13', while the discharge of liquid into the interior of the case may be regulated at any time from the exterior of the casting owing to the arrangement of the regulating pin 54 in the screw plug 14'. The device of my present invention can be employed 115 with equal facility for right-hand and left-hand doors, and it provides a simple, practical and efficient construction whereby to close the door from either direction to its initial position of rest without causing the door to pass beyond its center line, either to the right or to the left.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifica-

tions as come within the scope of the appended claims.

I claim:

1. A device of the character described having, in combination, a case, a stationary stem body, a movable cylinder slidably embracing the stem body and forming a liquid checking chamber therewith, a sleeve movable with the cylinder and forming a by-pass chamber with the stem body, spring means normally urging the cylinder and sleeve to one terminal of movement, said stem body having by-pass channels therein adapted to establish and disestablish communication with the by-pass chamber, one of said channels being in communication with the liquid checking chamber and the other being in communication with the interior of the case, and a regulating valve for the channel that is in communication with the interior of the case.
2. A device of the character described having, in combination, a case, a stationary stem body, a movable cylinder slidably embracing the stem body and forming a liquid checking chamber therewith, said stem body having a by-pass leading from the liquid checking chamber to the interior of the case, said by-pass including two separate and unconnected channels and a port for each channel opening through the circumference of the stem body, a spring normally urging the cylinder toward one terminal of movement, and means connected with the cylinder for establishing and disestablishing communication between said ports, said means being arranged to disestablish communication therebetween as the cylinder is forced to a position relatively close to its terminal of movement.
3. A device of the character described having, in combination, a case, a stationary stem body, a movable cylinder slidably embracing the stem body and forming a liquid checking chamber therewith, and an entrance to the liquid checking chamber, said stem body having a by-pass leading from the liquid checking chamber and opening through a port into the interior of the case, said by-pass including two separate and unconnected channels and a port for each channel opening through the circumference of the stem body, a spring normally urging the cylinder toward one terminal of movement, means movable with the cylinder for establishing and disestablishing connection between said circumferential ports, said means being arranged to disestablish communication therebetween as the cylinder is forced to a position in proximity to its terminal of movement, a regulating valve for the port that opens into the interior of the case, and a ball check valve controlling the entrance to the liquid checking chamber.
4. In a device of the character described, consisting of a hollow case and a pintle operated cylinder therein, a stem body slidably embraced by the cylinder and forming there-

with an end chamber and a by-pass chamber, two separate channels in the stem body adapted respectively to provide communication between the end chamber and the by-pass chamber and between the by-pass chamber and the interior of the case, said channels in conjunction with the by-pass chamber forming a through by-pass between the end chamber and interior of the case.

5. In a device of the character described, consisting of a hollow case and a pintle operated cylinder therein, a stem body slidably embraced by the cylinder and forming therewith an end chamber, an annular chamber and a by-pass chamber, two separate channels in the stem body, one of which provides communication between the end chamber and a port adapted to communicate with the by-pass chamber and the other of which provides communication between the interior of the case, and a port adapted to communicate with the by-pass chamber said ports when in communication with the by-pass chamber providing in conjunction with the channels and by-pass chamber a through by-pass between the end chamber and the interior of the case, and a ledge between said by-pass chamber and annular chamber adapted to cover at least one of said ports when the cylinder is in one position.

6. In a device of the character described, the combination with a pintle operated cylinder, of a stem body slidably embraced by the cylinder and forming therewith a compression chamber and a by-pass chamber, two separate channels in the stem body, one leading from the compression chamber and the other leading to a point exteriorly of the cylinder, both of said channels having ports adapted to open communication with the by-pass chamber, said by-pass chamber being of such length with respect to the extent of the cylinder stroke that said ports will be substantially closed when the cylinder is in one position.

7. In a device of the character described, the combination of a case, a stem body fixed therein and having an inlet by-pass channel and an outlet by-pass channel, each channel having a lateral port intermediate the length of the stem body, a pintle actuated cylinder in the case slidably embracing the stem body and forming therewith an end chamber in communication with the inlet channel and also a by-pass chamber with which said ports are adapted concurrently to communicate, and a ledge adjoining the by-pass chamber adapted substantially to cover the ports when the cylinder is in relatively close proximity to one terminal of movement.

8. In a device of the character described, the combination with a case and a pintle reciprocated cylinder therein, of a stem body fixed within the case and slidably embraced by said cylinder, the stem body forming an

end chamber with the cylinder and having an inlet by-pass channel in communication with the end chamber and an outlet by-pass channel in communication with the interior of the case, a sleeve slidably embracing the stem body and attached to the cylinder and therewith movable, said sleeve forming a by-pass chamber with the stem body, and lateral ports for said inlet and outlet by-pass channels establishing communication with said by-pass chamber and adapted to be covered by said sleeve when the latter is in relatively close proximity to one terminal of movement.

In testimony that I claim the foregoing as my invention, I have signed my name hereto.

EMIL BOMMER.
